CLUB HOLDER FOR A GOLF BAG

William G. Christie, 1301 E. Michelle St.,
West Covina, Calif. 91790

Filed Oct. 3, 1967, Ser. No. 8,852

Term of patent 14 years

(Cl. D34—5)

FIG. 1 is a side elevational view of a club holder for a golf bag showing my new design when incorporated in a golf bag which is shown in broken lines for illustrative purposes only; and

FIG. 2 is a perspective view of the club holder.

I claim:

The ornamental design for a club holder for a golf bag, as shown and described.
